TUBE CLOSURE

John M. Schooley, Madison, Ill., assignor of one-half to Harry O. Schooley, Madison, Ill.

Application July 31, 1933, Serial No. 682,973

5 Claims. (Cl. 221—60)

This invention relates to closures, and more particularly to closure devices for collapsible tubes, such as for example, tooth paste tubes and the like.

5 The principal object of the present invention is to provide a collapsible tube closure device which will seal the discharge opening through the neck of the tube when the device is closed and prevent escape of the contents from the tube even though 10 considerable pressure be applied thereto.

Other objects are to provide a tube closure device that can be readily manipulated to open and close the discharge opening; that is simple in construction; and that is comparatively inexpensive 15 to manufacture.

The invention consists in the collapsible tube closure device, and in the parts, combinations, and arrangements of parts hereinafter described and claimed.

20 In the accompanying drawing, which forms part of this specification, and wherein like reference symbols refer to like parts wherever they occur,

Fig. 1 is a top plan view of a collapsible tube equipped with a closure device embodying my invention;

Fig. 2 is a side view of Fig. 1;

Fig. 3 is a vertical section along the line 3—3 in Fig. 2;

Fig. 4 is a vertical section along the line 4—4 in 30 Fig. 1 with the closure device shown in closed position;

Fig. 5 is a view similar to Fig. 4 with the closure device shown in open position;

Fig. 6 is a perspective view of the sealing cup member of the closure device; and

Fig. 7 is a perspective view of a modified form of sealing cup member.

In the drawing is shown a collapsible tube 1 which is provided with a relatively stiff conical 40 end portion 2 having a bell-shaped neck 3. The neck 3 has a cylindrical discharge opening 4 extending therethrough and opening into the inside of the tube 1, and a sealing cup member generally designated as 5 and made of flexible material, such 45 as rubber or the like, is disposed in the discharge opening 4 through the neck of the tube.

The sealing cup member, shown in Figs. 1 to 6, inclusive, of the drawing, comprises a hollow cylindrical or tubular body portion 6 that has an integral closed flat disc-like outer end portion 7. The sealing cup member does not fit tightly in the discharge opening 4, but it is made of such diameter, with respect to the diameter of the discharge opening, that it will move axially therein if pressure is applied to either of its ends. The flat end

portion of the sealing cup member has a U-shaped valve slit 8 therein forming a flap 9 which is adapted to open up and form a valve opening 10 for allowing passage of the contents of the tube when it is desired to remove the contents therefrom.

5 In order to keep the flap 9 closed and thus keep the discharge opening 4 of the tube sealed against removal of the contents, a flat metallic closure member 11 is mounted on the tube neck adjacent to the flat outer end portion of the sealing cup member for sliding movement across the discharge opening. While the closure member may be slidably mounted on the tube neck in any suitable manner, I prefer to provide the end of the tube neck with two ears 12 located at opposite 10 sides of the discharge opening 4 through the neck, and the closure member is mounted for sliding movement between said ears and the end of the tube neck. Preferably, the ears 12 may be beveled 15 as at 13 so that the tube neck may be wiped without any appreciable discomfort to the fingers of the user.

Each end of the closure member is provided with a flange 14 extending toward the conical end portion of the tube; and these flanges are 25 arranged to engage opposite sides of the tube neck for stopping the closure member in open and closed positions; and the closure member has an outlet opening 15 near one end in position to register with the valve slit 8 through the flat end 30 portion of the sealing cup member when the closure member is moved into open position.

In order to keep the closure member in closed position, a groove 16 is provided in the conical end portion of the tube adjacent to the tube neck so 35 that when the closure member is moved into closed position, the lower end of the flange 14 opposite the end provided with the outlet opening will snap into such groove and keep the closure member locked in such position. Obviously, if 40 desired, a similar arrangement could be provided to keep the closure member locked in open position.

In some instances, where the tube is to contain a comparatively thin paste or liquid matter, it 45 may be preferable to use a sealing cup member of the form shown in Fig. 7. This form of sealing cup member is similar in all respects to the form shown in Figs. 1 to 6, inclusive, with the exception that a straight valve slit 8a is provided in the 50 flat outer end portion of the sealing cup member instead of the U-shaped valve slit.

With a tube closure conforming to my invention, when the closure member is closed, the discharge opening of the tube is completely sealed.

and the contents thereof cannot be forced therefrom even though considerable pressure be applied to the tube. If the closure member is closed, and pressure is accidentally applied to the tube during handling thereof, such pressure will force the contents thereof into the sealing cup member and thus press the flat end portion thereof flat against the closure member to completely close up the valve slit and also force the wall of said sealing cup member tightly against the wall of the discharge opening to thoroughly seal the same.

In order to use the tube, all that is necessary to do is to move the closure member into open position, which can be readily accomplished by a mere "flip" of the user's thumb, and then to apply pressure to the tube. Such pressure will force the contents of the tube through the valve slit which is free to open up when it is in register with the closure member which is the case when such member is opened.

Obviously, the tube closure construction hereinabove described admits of considerable variations without departing from the scope of the invention; accordingly, I do not wish to be limited to the precise constructions shown and described.

I claim:

1. The combination of a collapsible tube having a discharge opening, a flexible sealing member having a valve slit disposed in said opening, said sealing member being free to move axially therein, and a closure member movably mounted on said tube and adapted to move across said opening adjacent to the valve slit in said sealing member.

2. The combination of a collapsible tube having a discharge opening, a flexible sealing cup member mounted therein, said member comprising a tubular body portion being free to move axially in said opening and having a closed flat outer end portion provided with a valve slit therein, and a flat closure member movably mounted on said tube and adapted to move across said discharge

opening adjacent to the outer end portion of said sealing cup member.

3. The combination of a collapsible tube having a discharge opening, a flexible sealing cup member disposed in said opening, said sealing cup member comprising a tubular body portion having a closed flat outer end portion provided with a valve slit therein, and a flat closure member mounted on said tube for sliding movement across said discharge opening adjacent to the outer end of said sealing cup member and having an outlet opening in position to register with the valve slit in the sealing cup member.

4. The combination of a collapsible tube having a discharge opening, a flexible sealing member having a valve slit disposed in said opening, and a closure member mounted on said tube for sliding movement across said discharge opening adjacent to the outer end of said sealing member and having an outlet opening in position to register with the valve slit in the sealing member.

5. The combination of a collapsible tube provided with a conical end portion having a neck extending therefrom, said neck having a discharge opening extending therethrough and communicating with the inside of said tube, a rubber sealing cup member disposed in said opening, said sealing cup member comprising a tubular body portion extending around the wall of said discharge opening and having a closed flat disc-like outer end portion provided with a valve slit therein, a pair of ears provided on the end of the tube neck at opposite sides of the discharge opening therethrough, and a flat closure member mounted for sliding movement between said ears and the end of the tube neck and having an outlet opening therethrough, said closure member having flanges at its ends extending toward the conical end portion of the tube, and said conical end portion having a groove therein for accommodating the end portion of one of said flanges.

JOHN M. SCHOOLEY.
